ROLLER-MILL FEED REGULATOR

Willy Löffler, Uzwil, Switzerland, assignor to
Gebrüder Bühler, Uzwil, Switzerland

Application November 28, 1951, Serial No. 253,667

Claims priority, application Switzerland
December 9, 1950

4 Claims. (Cl. 222—58)

1

My present invention relates to improvements in means for regulating the rate of feed through a pivoted segmental gate of a roller mill.

In known regulators of this kind, a regulating element connected to the gate through a linkage and biased through the outflowing grain, tends to open the gate against the action of a spring. Such known regulators generally are of such sensitivity as to give origin to a "pumping action" whereby the gate is pulsatingly opened and closed so as to affect very unfavorably the power input of the mill units and of the entire mill.

Such known regulator elements, furthermore, generally are formed as inclined clacks or toggle levers which project far into the hopper space, or are formed as firtree-like gable structures, which project upwardly into the glass cylinder. These known regulator elements have a great disadvantage in that the outflowing goods tend to accumulate below them whereby nests of moths may be formed which impair the regulation i. e. prevent the segmental gate from being entirely opened. In some of these known regulators, furthermore, the goods to be ground have to be retained in the hopper to a level high up in the glass cylinder in order to allow the goods to be distributed over the entire length of the delivery rollers.

Such disadvantages inherent to known regulators shall be eliminated by means of the feed regulator disclosed in my present invention in that the regulating element is formed by at least one piece of corrugated sheet iron which hangs freely in the hopper and of which the corrugations extend substantially parallel to the delivery rollers so that the goods acting on to the corrugated faces cause the delivery gate to be opened and closed uniformly smoothly.

One form of my present invention is shown by way of example in the accompanying drawing in which:

Fig. 1 shows a vertical cross-section through the hopper of a roller mill in operation, the segmental delivery or feed gate (6) being open, and

Fig. 2 is a vertical longitudinal section on the line II—II of Fig. 1, illustrating the heap of goods retained in the hopper.

The hopper 1 is defined by the space above the delivery or feed rollers 2 and between the two stationary walls 3 and 4, while 5 is the feed trough. The segmental feed gate 6 on one hand has an upwardly projecting arm 7 fixed thereto, which carries an adjustable finger 8 to one end of which is pivoted a roller 8'. The gate 6 on the other hand is biased by a regulable tension spring 9 to the closed position. To a regulating shaft 10 are fixed an arm 11 which has a track for the roller 8', and a baffle or cover sheet 12. The latter extends through the entire length of the hopper 1, i. e. it is as long as the feed rollers 2.

2

To the baffle 12 are fixed two arms 13 in which is rotatably mounted a rod 16 to which are fixed two regulating elements 14. Each of the latter consists of a piece of corrugated sheet iron of which the corrugations run either parallel to the feed rollers 2 or slightly slope downwardly towards the ends thereof. The corrugation faces of each element 14 are inclined at an angle of approximately 30° with respect to the vertical plane through the rod 16. The latter is journaled in recesses of the two arms 13 so as to be readily removable therefrom. The confining wall 4 is fixedly arranged, but is readily removable. Above the hopper 1 is disposed a glass inflow cylinder 15 of known construction through which the goods run into the hopper 1.

The mode of operation of the regulator described is as follows:

Since the baffle 12 here is shortened to such an extent that practically no goods can accumulate below the same and below the wall 4, the entire hopper space 1 is free of baffles and like means and the inflowing goods can unimpededly move downwardly to the segmental gate 6. The two regulating elements 14, which are interconnected through the rod 16, do not disturb the downward flow of the goods, but on the contrary aid the uniform distribution of the goods over the entire length of the rollers 2.

When the goods are heaped up in the hopper 1, they act laterally on to the corrugations of the elements 14, as shown by the little arrows in Fig. 1, and tend to push the same downwardly against the action of spring 9, with the result that the gate 6 is slowly and gently opened. When the heap in hopper 1 decreases in height the reaction of the two elements 14 is delayed so that the gate 6 is reclosed only slowly and gradually.

When the goods are delivered to the hopper 1 at an irregular rate, the regulator 6—14 does not react or only so little as to practically exclude any pumping action or pulsating delivery. When emptying the hopper 1, the goods still react on the lowermost corrugations of the two elements 14 so as to hold the gate still slightly open until the hopper 1 is entirely empty.

When there are no more goods in hopper 1, the two regulating elements 14 together with the two arms 13 are in their topmost position, and the gate 6 is entirely shut. When, however, the roller mill is fully loaded, the said elements and arms are in their bottommost position without, however, touching the rotary feed roller 2. The heaping level of the goods in the hopper 1 may be adjusted, as desired, by changing the tension of the spring 9 of gate 6. Normally in operation, the goods still should be visible in the lower portion of the glass cylinder 15 in order to allow the attendant to control the throughput.

The spacing between the two regulating elements 14 is somewhat smaller than the diameter of the glass cylinder 15 in the case of short roller mills, and approximately equal to said diameter in the case of long mills. The said spacing as well as the width of the elements 14 are essential for a good distribution of the goods over the entire length of hopper 1.

Dynamometer tests have disclosed that a roller mill equipped with the novel feed regulator described, requires less power input than a roller mill equipped with a conventional regulator in which troublesome load fluctuations arise on account of the pulsating or "pumping action" feed.

What I claim as new and desire to secure by Letters Patent, is:

1. In a roller mill feed regulator having a hopper with multiple walls, said hopper being open at its top for the receipt of the goods to be ground, feed rollers at the bottom of said hopper and a spring regulated gate adjacent to the feed rollers, said feed rollers and said gate closing said bottom, a baffle in the path of said goods while they descend downwardly by gravity, and linkage between said baffle and gate extending outside of said hopper to open or close the gate, the combination of a supporting member on said baffle extending inwardly of said hopper, a gate regulating member pivotally connected with said supporting member and disposed in the approximate median of said goods in said hopper and extending vertically downwardly towards and in proximity to said gate and to one of said feed rollers, said regulating member being in the form of at least one plate of corrugated sheet iron, of which the corrugations extend substantially parallel to said feed roller, whereby on the goods descending in the hopper space, free of any impeding means and unimpededly to said gate, the goods act laterally on said corrugations, which tend to push said plate downwardly to slowly and gently open said spring controlled gate, and when goods diminish in their flow with less push against said corrugations, said gate slowly and gradually closes, said opening and closing of said gate taking place practically without any pumping action or pulsating delivery of the gate.

2. In a roller mill feed regulator having a hopper with multiple walls, said hopper being open at its top for the receipt of the goods to be ground, feed rollers at the bottom of said hopper and a spring regulated gate adjacent to the feed rollers, said feed rollers and said gate closing said bottom, a baffle in the path of said goods while they descend downwardly by gravity, and linkage between said baffle and gate extending outside of said hopper to open or close the gate, the combination of a supporting member on said baffle extending inwardly of said hopper, two regulating plates with corrugations in said hopper, said regulating plates being spaced from each other and being pivotally connected with said supporting member, and disposed in the approximate median of said goods in said hopper and extending vertically downwardly towards and in proximity to said gate and to one of said feed rollers, and a series of downwardly inclined faces on said plates, substantially parallel to said feed rollers, whereby on the goods descending in the hopper space, free of any impeding means and unimpededly to said gate, the goods act laterally on said faces of said regulating plates, whereby said plates tend to move downwardly to slowly and gently open said spring controlled gate, and when the goods di-

minish in their flow with less push against said faces, said gate slowly and gradually closes, said opening and closing of said gate taking place practically without any pumping action or pulsating delivery of the gate.

3. In a roller mill feed regulator having a hopper with multiple walls, said hopper being open at its top for the receipt of the goods to be ground, feed rollers at the bottom of said hopper and a spring regulated gate adjacent to the feed rollers, said feed rollers and said gate closing said bottom, a baffle in the path of said goods while they descend downwardly by gravity, and linkage between said baffle and gate extending outside of said hopper to open or close the gate, the combination of a supporting member on said baffle extending inwardly of said hopper, a gate regulating plate pivotally connected with said supporting member, and disposed in the approximate median of said goods in said hopper and extending vertically downwardly towards and in proximity to said gate and to one of said feed rollers, and a series of corrugations on said regulating plate, said corrugations being longitudinally slightly inclined towards the two ends of the feed rollers, whereby on the goods descending in the hopper space, free of any impeding means and unimpededly to said gate, the goods act laterally on said corrugations, thereby tending to push said plate downwardly to slowly and gently open said spring controlled gate, and when the goods diminish in their flow with less push against said corrugations, said gate slowly and gradually closes, said opening and closing of said gate taking place practically without any pumping action or pulsating delivery of the gate.

4. In a roller mill feed regulator having a hopper with multiple walls, said hopper being open at its top for the receipt of the goods to be ground, feed rollers at the bottom of said hopper and a spring regulated gate adjacent to the feed rollers, said feed rollers and said gate closing said bottom, a baffle in the path of said goods while they descend downwardly by gravity, and linkage between said baffle and gate extending outside of said hopper to open or close the gate, the combination of a supporting member on said baffle extending inwardly of said hopper, a gate regulating plate pivotally connected with said supporting member, and disposed in the approximate median of said goods in said hopper and extending vertically downwardly towards and in proximity to said gate and directly above one of said feed rollers, and a series of downwardly inclined faces on said plate, substantially parallel to said feed rollers, whereby on the goods descending in the hopper space, free of any impeding means and unimpededly to said gate, the goods act laterally on said faces, thereby tending to push said plate downwardly to slowly and gently open said spring controlled gate, and when the goods diminish in their flow with less push against said faces, said gate slowly and gradually closes, said opening and closing of said gate taking place practically without any pumping action or pulsating delivery of the gate.
